UNITED STATES PATENT OFFICE

GOTTLIEB J. HERMAN, OF ORRVILLE, OHIO

PICKLING RECEPTACLE

Application filed September 29, 1928. Serial No. 309,188.

The present invention relates to improvements in receptacles and has reference more particularly to a container for use in pickling food products such as vegetables, meats.

One of the important objects of the present invention is to provide a pickling receptacle that includes a means for facilitating the draining of the liquid whereby the food products undergoing the pickling action may be removed from the receptacle without removing the brine or chemically treated liquid with such products.

Still a further object is to provide a pickling receptacle of the above mentioned character which is simple in construction, inexpensive, strong and durable and further well adapted to the purposes for which it is designed.

Other objects and advantages will become apparent during the course of the following description.

In the accompanying drawing, forming a part of this specification, and in which like numerals indicate like parts throughout the same:

Figure 1 is a side elevation of the pickling receptacle embodying my invention,

Figure 2 is a similar view, the auxiliary receptacle being shown in section to more clearly illustrate the drain holes formed in the side of the main receptacle,

Figure 3 is a vertical sectional view taken approximately on the line 3—3 of Figure 1, and

Figure 4 is a transverse section taken substantially upon the line 4—4 of Figure 3.

In the drawing wherein for the purpose of illustration is shown the preferred embodiment of my invention, the numeral 1 designates a substantially cylindrical main receptacle that may be constructed of stone ware, wood, metal or any other suitable material. This main receptacle is preferably open at its top and is formed in its side with a series of staggered drain openings 2 that extend for the entire height of the main receptacle as is clearly illustrated in Figures 2 and 3 of the drawings.

A substantially semi-cylindrical auxiliary receptacle 3 is secured to the outer face of

the main receptacle 1 for disposition over the openings or holes 2 and attaching flanges 4 are formed on the free edges of said semi-cylindrical auxiliary receptacle which flanges are soldered or otherwise secured to the outer surface of the main receptacle to provide a leak-proof connection between the receptacles.

The auxiliary receptacle is closed at its lower end while the upper end thereof is open and said auxiliary receptacle is of substantially the same height as the main receptacle.

A cover or lid 5 is provided for the main and auxiliary receptacle and this cover is preferably of the split type whereby the same can be readily and easily applied or removed.

While I have shown the receptacle 1 as being substantially cylindrical and the auxiliary receptacle 3 being semi-cylindrical, it is to be understood that I do not wish to limit myself to the particular shape of said receptacle as the same may be of any desirable contour. A false bottom 6 is removably arranged within the main receptacle 1 and supporting a seat 7 to space the false bottom 6 with respect to the bottom of the main receptacle in the manner as clearly suggested in Figure 3.

The false bottom is formed with a series of spaced drain holes 8 and this feature is more clearly illustrated in Figure 4.

A drain cock 9 extends from the outer side of the auxiliary receptacle 3 and this drain cock is preferably located adjacent the lower end of said auxiliary receptacle and furthermore at a point below the false bottom 6 as indicated in Figure 3.

In use, the products to be pickled are placed in the main receptacle 1 and the false bottom will keep said products away from the bottom of the main receptacle. The pickling fluid is then poured into the main receptacle and by reason of the drain holes 2, the liquid will enter the auxiliary receptacle 3 so that the same level will be present in both receptacles. The pickling liquid can be drained from the receptacles by opening the cock 9 and after all of the liquid has been drained, the pickled products can be readily and easily removed from the main receptacle after 100.

which the pickling liquid can again be used for further pickling purposes.

Also in case of an excess of amount of the pickling liquid, being present in the receptacles, such excess supply may be drained off without necessitating the handling of the pickling receptacle.

It will thus be seen from the foregoing description, that I have provided a pickling receptacle that will efficiently serve the purpose for which it is designed and due to its simplicity, the device can be readily and easily cleaned whenever necessary.

While I have shown the preferred embodiment of my invention, it is to be understood that various changes in the size, shape and arrangement of parts may be resorted to without departing from the spirit of the invention and the scope of the appended claims.

Having thus described my invention, what I claim as new is:

1. A pickling receptacle comprising a container having a longitudinally extending offset portion forming an auxiliary receptacle, said container and auxiliary receptacle having an intervening wall perforated to provide drain openings, a drain cock at the lowest end of the auxiliary receptacle, and a perforated false bottom member removably positioned within the container.

2. In a pickling device, a main receptacle, a relatively smaller auxiliary receptacle disposed longitudinally of the outer side of the main receptacle for substantially the full height of the latter, said main receptacle having that portion of the wall intervening between the main and auxiliary receptacle perforated to provide drain holes between the receptacle, said main and auxiliary receptacles being open at the top and closed at the bottom, a perforated false bottom removably disposed in the main receptacle in spaced relation to the bottom thereof, a drain cock extending from the lower end of the auxiliary receptacle at a point below the level of the false bottom, and closure means for the said open top of the said main and auxiliary receptacle.

50. In testimony whereof I affix my signature.
GOTTLIEB J. HERMAN.
